Term of patent 7 years

(CL. D19—1)

Fig. 1

Fig. 3

FIG. 1 is a perspective view of a burial vault cover embodying my design;

FIG. 2 is a side elevational view thereof; and

FIG. 3 is a section taken on line 3—3 of FIG. 2.

The characteristic feature of my design resides in the combination on the burial vault disclosed, of the particular double flange at the bottom in association with the ogee top, all as shown.

I claim:

The ornamental design for a burial vault cover, substantially as shown and described.
